UNITED STATES PATENT OFFICE.

OTTO CAESAR, OF NEW YORK, N. Y.

WINDOW-CLEANER.

No. 887,585.

Specification of Letters Patent. Patented May 12, 1908.

Application filed March 26, 1907. Serial No. 364,610.

To all whom it may concern:

Be it known that I, OTTO CAESAR, a citizen of the United States, and a resident of the city of New York, (Long Island City, borough of Queens,) in the county of Queens and State of New York, have invented a new and Improved Window-Cleaner, of which the following is a full, clear, and exact description.

10 The object of the invention is to provide a new and improved window cleaner, arranged to permit convenient and thorough cleaning of the window sash, both on the inside and outside, and without the slightest danger to 15 the operator.

The invention consists of novel features and parts and combinations of the same, which will be more fully described hereinafter and then pointed out in the claims.

20 A practical embodiment of the invention is represented in the accompanying drawings forming a part of this specification, in which similar characters of reference indicate corresponding parts in all the views.

25 Figure 1 is a front elevation of the improvement as applied; Fig. 2 is a longitudinal section of Fig. 1; Fig. 3 is an enlarged inverted plan view of the improvement, part being shown in section; Fig. 4 is an enlarged sectional side elevation of the outer wiping device; Fig. 5 is a front view of the inner wiping device, and Fig. 6 is a transverse section of the improvement on the line 6—6 of Fig. 3.

The main frame A of the window cleaner 35 is U-shaped and consists of the middle bar A' and the side arms A², A³, adapted to straddle the window sash B, as plainly illustrated in Figs. 1 and 2, that is, the side arm A² extending on the outside of the window sash, 40 while the side arm A³ is on the inside of the window sash, and the cross bar A' is arranged transversely below the bottom of the partly open sash. The middle bar A' of the main frame A is provided at its ends with trunnions A⁴ engaging a bearing C mounted to 45 slide on a rod D extending between the sides of the window frame B', and provided at its ends with angular arms D', D² having longitudinally extending trunnions D³, D⁴ adapted 50 to engage keepers E and E', preferably in the form of sockets, secured to the parting strips B² on the sides of the window frame B', as plainly indicated in Figs. 1 and 2. Now by 55 having the angular arms D', D², the rod D may be readily brought directly under the lower sash, as indicated in Figs. 1 and 2; or

the rod may be swung outward, so as to bring the same directly under the upper sash, as indicated in dotted lines in Fig. 2. Thus by the arrangement described, the device can 60 be brought into proper alignment with the lower sash when it is desired to clean the latter, as hereinafter more fully described.

The outer or free end of the side arm A² of the main frame A is provided with a bearing 65 for the transverse pivot F' of a swing arm F, and the outer end of the side arm A³ of the main frame A is provided with a bearing for the transverse pivot G' of a swing arm G, the swing arms F and G being provided with 70 wipers H and I adapted to engage the glass pane of the window sash, to wipe, rub and clean the same both at the inside and outside of the window, and simultaneously, if desired. 75

Now in order to actuate the outer swing arm F in unison with the inner swing arm G controlled by the operator, the pivotal ends of the swing arms F and G are provided with drums or grooved pulleys J and J', on which 80 winds a cable, rope or like flexible connection K, also passing over a set of tension pulleys K' held on the side arm A² and over sets of guide pulleys K², K³ and K⁴, K⁵ journaled on the cross bar A' of the main frame A, adjacent to the corresponding side arms A², A³. The ends of the cable K are rigidly secured to one of the drums J or J', so as to practically render the cable endless, and by mounting the tension pulleys K' on a frame 90 K⁶ held adjustably on the side arm A², it is evident that the desired tension can be given to the cable K, and hence when a swinging motion is given to the swing arm G then the cable K is caused to travel and to impart a 95 like swinging motion to the swing arm F, so that the latter moves in unison with the swing arm G.

Now in order to manipulate the device a simultaneous swinging motion is given by 100 the operator to the side arm A³ and the swing arm G, which are both provided for this purpose with suitable handles L and L', adapted to be taken hold of by the operator with both hands. Now on swinging the 105 main frame A and at the same time imparting a simultaneous swinging motion to both swing arms G and F, it is evident that each and every part of the pane of the window sash can be reached by the wiping devices H 110 and I, in order to clean the same both at the inside and outside. The swing arm F is pref-

erably made in the form of two tubes, in the outer ends of which telescope the rods H' , also passing through split sleeves F' having a clamping screw F^2 for securing the rods H' in place after the same have been adjusted, to bring the wiper H into the desired position for cleaning a certain sized window. Thus for smaller windows the rods H' are telescoped inward in the swing arm F and for larger windows the rods H' are extended or drawn outward. The outer ends of the rods H' are connected with each other by a socket H^2 for removably receiving the angular frame H^3 , supporting a body plate H^4 of sheet metal or a like material, and inclosed in a pocket H^5 made of a suitable fabric material for engagement with the window pane. The body plate H^4 as well as the covering H^5 are approximately of triangular shape, as indicated in Fig. 1, so as to permit of conveniently reaching and thoroughly cleaning the corners of the window sash. The pocket H^5 is held removably on the body plate H^4 and it is readily secured in place on the body plate by buttoning it to a button H^6 , as indicated in Fig. 4. The angular frame H^3 is provided with a spring tongue H^7 adapted to snap under a cross bar or keeper H^8 held on the socket H^2 , to hold the wiper H against dis- placement, at the same time permitting the removal of the wiper from the socket H^2 whenever it is desired to change the same. The swing arm G is likewise made of a pair of tubes into which telescope the rods I' (see Fig. 5), the rods I' terminating at their outer ends in a loop I^2 having a catch I^3 for receiving and holding an arm I^4 fulcrumed on a cross piece I^5 connecting the rods I' with each other. A spring I^6 held on the cross piece I^5 presses the arm I^4 in an inward direction, and the said arms I^4 are provided with a socket I^7 , for removably supporting a spring frame I^8 carrying a body plate similar to the body plate H^4 and covered by a covering I^9 similar to the cover H^5 . The frame I^8 is also provided with a spring tongue I^{10} similar to the spring tongue H^7 , so that further description of the same is not deemed necessary. Now by the arrangement described the wiper I^9 is pressed into engagement with the inside of the window pane by the action of the spring I^6 , and whenever it is desired not to make use of this wiper I^9 it is only necessary for the operator to swing the arm I^4 outward and engage the same with the spring catch I^3 to hold the wiper in an inactive position, as indicated in dotted lines in Fig. 3. It is evident, however, that when the wiper is in its inactive position, the arm G and frame A are manipulated in the same manner as previously mentioned, so as to cause the outer wiper H to clean the outer face of the window pane whenever it is desired to do so.

It will also be noticed that by the operator moving the bearing C lengthwise on the sup-

porting rod D and swinging the frame A as well as the swing arm G in the desired direction, any and every part of the window pane can be reached, for cleaning the same both on the inside and outside or on the outside only, if desired. 70

It will also be noticed that by having the retractable trunnion D^3 (see Fig. 3) the supporting rod D can be readily engaged with or disengaged from the keepers E , E' , to allow ready use of the device on any window, and to permit convenient disengagement of the device from one window and transferring it to another window. 75

In order to prevent a too easy sliding of the bearing C on the supporting rod D , a spring C may be employed, attached to the bearing C and pressing on the supporting rod D , as indicated in Figs. 1 and 3. 80

Now from the foregoing it will be seen that the operator stands inside of the room and conveniently manipulates the device, to readily clean the window pane both at the inside and outside, without the slightest danger to the operator. 85

Having thus described my invention, I claim as new and desire to secure by Letters Patent:

1. A window cleaner comprising a guideway for attachment to the window casing, a bearing slidably mounted on the said guideway, a U-shaped rock frame having its middle portion fulcrumed on the said bearing, the side arms of the frame straddling the window sash, swing arms mounted to swing on the free ends of the said side arms, and means connecting the said swing arms with each other by way of the said frame. 90

2. A window cleaner comprising a guideway for attachment to the window casing, a bearing slidably mounted on the said guideway, a U-shaped rock frame having its middle portion fulcrumed on the said bearing, the side arms of the frame straddling the window sash, swing arms mounted to swing on the free ends of the said side arms, means connecting the said swing arms with each other by way of the said frame, and wipers on the ends of the said swing arms. 105

3. A window cleaner comprising a guideway for attachment to the window casing, a bearing slidably mounted on the said guideway, a U-shaped rock frame having its middle portion fulcrumed on the said bearing, the side arms of the frame straddling the window sash, swing arms mounted to swing on the free ends of the said side arms, means connecting the said swing arms with each other by way of the said frame, wipers on the ends of the swing arms, and means for holding one 110 of the wipers in inactive position. 120

4. A window cleaner comprising a guideway for attachment to the window casing, a bearing slidably mounted on the said guideway, a U-shaped rock frame having its mid- 130

dle portion fulcrumed on the said bearing, the side arms of the frame straddling the window sash, swing arms mounted to swing on the free ends of the said side arms, the outermost swing arm carrying a wiper, and the innermost swing arm and the innermost side arm being provided with handles for manipulating the window cleaner, and means connecting the said swing arms with each other 10 by way of the said frame.

5. A window cleaner comprising a guide-way for attachment to the window casing, a bearing slidably mounted on the said guide-way, a U-shaped rock frame having its middle portion fulcrumed on the said bearing, the side arms of the frame straddling the window sash, swing arms mounted to swing on the free ends of the said side arms, drums fixed on the fulcrum ends of the said swing 15 arms, guide pulleys on the middle portion of the said frame, and a cable passing around the said drums and pulleys.

6. A window cleaner comprising a guide-way for attachment to the window casing, a bearing slidably mounted on the said guide-way, a U-shaped rock frame having its middle portion fulcrumed on the said bearing, the side arms of the frame straddling the window sash, swing arms mounted to swing on 20 the free ends of the said side arms, drums fixed on the fulcrum ends of the said swing arms, guide pulleys on the middle portion of the said frame, a cable passing around the said drum and pulleys, the ends of the said 25 cable being secured to one of the said drums, and a tension device for the cable on one member of the rock frame.

7. A window cleaner provided with a swing frame for straddling the window sash, swing 40 arms fulcrumed on the said frame, drums on the fulcrum ends of the said swing arms, and a cable passing around the said drums and extending along the said frame.

8. A window cleaner provided with a swing 45 frame for straddling the window sash, swing arms fulcrumed on the said frame, drums on the fulcrum ends of the said swing arms, a cable passing around the said drums and extending along the said frame, and a wiper adjustably held on the outermost swing arm.

9. A window cleaner provided with a swing 50 frame for straddling the window sash, swing arms fulcrumed on the said frame, drums on

the fulcrum ends of the said swing arms, a cable passing around the said drums and extending along the said frame, a wiper adjustably held on the outermost swing arm, and a wiper mounted to swing transversely on the innermost swing arm. 55

10. A window cleaner provided with a swing frame for straddling the window sash, swing arms fulcrumed on the said frame, drums on the fulcrum ends of the said swing arms, a cable passing around the said drums and extending along the said frame, a wiper 60 adjustably held on the outermost swing arm, a wiper mounted to swing transversely on the innermost swing arm, and locking means for holding the said wiper on the innermost swing arm in an active or non-active position. 65

11. A window cleaner provided with a swing frame for straddling the window sash, swing arms fulcrumed on the said frame, drums on the fulcrum ends of the said swing arms, a cable passing around the said drums 70 and extending along the said frame, and a tightening device for tightening the said cable.

12. A window cleaner provided with a support comprising keepers on the window 80 frame, a rod provided with transverse arms, and longitudinally extending trunnions on the said arms for engagement with the said keepers.

13. A window cleaner provided with a support comprising keepers on the window frame, a rod provided with transverse arms, and longitudinally extending trunnions on the said arms for engagement with the said 85 keepers, one of the trunnions being retractable.

14. In a window cleaner, a swing frame, arms pivoted to the frame, means for swinging the arms in unison, wiper carrying members carried by said arms, one of the said 90 members being pivoted, and means for holding the said pivoted member in inactive position.

In testimony whereof I have signed my name to this specification in the presence of 100 two subscribing witnesses.

OTTO CAESAR.
